RESTAURANT BUILDING

Edwin H. Eichler, 910 Lake Shore Drive,
Chicago, Ill. 60611

Original design applications Sept. 22, 1964, Ser. No. 81,826, now Patent No. 205,061, dated June 21, 1966, and Dec. 13, 1965, Ser. No. 517, now Patent No. 205,931, dated Oct. 11, 1966. Divided and this application June 16, 1966, Ser. No. 3,271

Term of patent 14 years

(Cl. D13—1)

FIGURE 1 is a perspective view of a restaurant building showing my new design;

FIG. 2 is an elevation view of the side to the right in FIG. 1; and

FIG. 3 is an elevation view of the hidden side to the left in FIG. 1; and

FIG. 4 is a top plan view thereof on a reduced scale.

The dominant features of my design reside in the portions shown in full lines. The ornamental design is substantially symmetrical about the longitudinal axis.

The ornamental design of my restaurant building is generally characterized by a wheeled circus-wagon facade simulating barred cages with convoluted ornamental borders.

This is a division of Design application Ser. No. D517, filed December 13, 1965, now Patent No. D. 205,931 and is also a division of design application Ser. No. D. 81,826, filed September 22, 1964, now Patent No. D. 205,061.

I claim:

The ornamental design for a restaurant building, substantially as shown and described.
